UNITED STATES PATENT OFFICE

JOSEF RENES, OF VSETIN, CZECHOSLOVAKIA

LIQUID FUEL PUMP FOR INTERNAL COMBUSTION ENGINES

Application filed November 3, 1930, Serial No. 493,210, and in Great Britain May 27, 1930.

This invention relates to an improved liquid fuel pump for internal combustion engines designed to deliver variable quantities of fuel to the reservoir connected with the injecting nozzle, use being made therein of a well-known construction of piston which is provided with a radial hole or holes and with an axial or longitudinal hole, the latter being in communication with the said radial holes and with the working space of the pump and the radial holes being adapted during the movement of the piston to be placed in communication with the suction chamber of the pump.

The object of the present invention is to provide an improved construction of fuel pump capable of being readily and accurately adjusted to supply variable quantities of fuel, in which the grinding in and polishing out are greatly simplified.

It has previously been proposed, in a fuel pump provided with a piston of the character above referred to, to mount a slidable sleeve or a rotary sleeve provided at one or both of its ends with V-shaped apertures or inclined faces, on the said piston for the purpose of varying the time during which the radial holes in the piston are kept in communication with the suction chamber of the pump.

The invention consists in a liquid fuel pump for internal combustion engines provided with a piston of the character referred to, in which the cylinder wherein the piston moves comprises two stationary parts, the end of one of which abuts against the end of the other part and is cut along two or more inclined or helical surfaces to produce a free space of variable height with respect to the radial holes in the piston and the piston being adapted to be adjusted in the circumferential direction of the two cylinders.

While the period of injection is controlled by the inclined or helical surfaces formed at the end of one of the stationary parts of the cylinder in co-operation with the radial holes provided at a certain distance from the end of the piston facing the working chamber of the pump, the starting of the injection is controlled by the said end of the piston in co-

operation with radial holes provided in the part of the cylinder constituting the working chamber.

The invention also consists in the improved construction of liquid fuel pump substantially as hereinafter described with reference to the accompanying drawings, in which

Figure 1 is a sectional elevation of the improved fuel pump, whilst

Figure 2 is a diagram illustrating the adjustment of the period of injection by means of the inclined surfaces formed at the end of one part of the cylinder.

Referring to the drawings, *a* is the casing or frame of the pump, *b* is a cylinder fixed in the casing *a* and *c* is another cylinder in axial alignment with the fixed cylinder *b* and secured thereto. *d* is the piston which is provided with radial holes *e* and with an axial or longitudinal hole *f*, the latter being in communication with the said radial holes *e* and with the working space *g* of the pump. During the movement of the piston, the radial holes *e* are adapted to be placed in communication with the suction chamber *h* of the pump. *i* are radial holes provided in the fixed cylinder *b*, through which communication is effected between the suction chamber *h* and the working space *g*, which communicates through a non-return valve *s* with the chamber from which the fuel is delivered to the injection nozzle. *i*₁ are longitudinal holes provided in the cylinder *b* through which the suction chamber *h* can additionally communicate with the working space *g* through a space left free between the cylinder *c* and the cylinder *b* and through the radial and longitudinal holes provided in the piston.

The cylinder *c* abuts with its end against the cylinder *b* and is cut, as is diagrammatically indicated in Figure 2, which is a development of the peripheral surface of the cylinder *c* and shows the position of the radial holes *e* in the piston relatively to the inclined cut surfaces *q* and *q*₁ at the end of the cylinder *c*. The piston *d* is adapted to be rotated by a rack and pinion *n*, *o* respectively, the latter being arranged to engage with the piston *d* by means of longi-

tudinal slots o_1 provided in the pinion and a transverse pin d_1 mounted in the piston d . As the piston d is rotated relatively to the cylinder c the moment at which the radial holes e will be uncovered will be varied and retarded over a distance e_1 or over a distance e_2 , according as to whether the holes e are in the position indicated by 1 or 2 relatively to the inclined surfaces at the end of the cylinder c , it being of course understood that the adjustment can be effected over the whole of the distance between 0 and 2.

A space r is left between the cylinder c and the casing of the pump, which space is in communication with the suction chamber h through the holes i_1 provided in the cylinder b .

The operation of the pump hereinbefore described is as follows:-

When the piston d is at the end of its working stroke, the radial holes e in the piston are in communication with the upper part of the free space left between the cylinders b and c . During the suction stroke, liquid fuel is sucked in from the suction chamber h and passed through the longitudinal hole f into the working chamber g . This suction takes place until the radial holes e in the piston are completely covered by the inclined surfaces q, q_1 cut in the upper end of the cylinder c . The further movement of the piston in a downward direction causes the radial holes i in the cylinder b to be uncovered, whereby further fuel is sucked in from the suction chamber. After the piston has reached the beginning of the working stroke and starts moving in an upward direction, the piston gradually covers the radial holes i in the cylinder b and when the said holes are completely covered, the fuel is forced by the piston from the working chamber g and past the non-return valve s into a chamber from which the fuel is delivered to the injection nozzle. The injection continues until the upper edge of the radial holes e provided in the piston reaches the inclined surfaces q, q_1 cut in the end of the cylinder c and the said radial holes are thereby uncovered. The fuel is thereupon pressed from the working space g of the pump into the suction chamber h and the non-return valve closes the communication between the working space and the delivery chamber which communicates with the injecting nozzle. It will thus be seen that the period of injection is controlled by the setting of the radial holes e in the piston relatively to the cut surfaces q, q_1 in the upper end of the cylinder c . As the piston continues its upward movement, fuel is forced from the working space into the suction chamber through the radial and longitudinal holes in the piston and also through the radial holes i provided in the cylinder b , until the latter holes are closed by the upper part of the piston whereupon the fuel opens the non-

return valve and is forced into the delivery chamber. This operation is continued until the piston reaches the end of its working stroke, whereupon the operation is repeated as above described.

I wish it to be understood that the details of construction may be modified without in any way departing from the spirit of the invention.

What I claim is:-

1. A liquid fuel pump for internal combustion engines having a stationary cylinder comprising the working chamber of the pump, another stationary cylinder the end of which abuts against the end of the other cylinder, the end of one of these two cylinders abutting against the other one having inclined surfaces, a piston capable of reciprocating within the said two cylinders and having a longitudinal hole in communication with the working chamber of the fuel pump and radial holes in communication with the said longitudinal hole and means for adjusting the said piston in the circumferential direction of the two cylinders in order to adjust the position of the radial holes in the piston relatively to the inclined surfaces provided at the end of one of the cylinders, the space left free between the said inclined surfaces and the end of the other cylinder being in communication with the suction chamber of the fuel pump, as and for the purpose set forth.

2. A liquid fuel pump for internal combustion engines as claimed in claim 1 and in which the cylinder comprising the working chamber has radial holes between the working chamber and the suction chamber of the pump arranged in such a position as to enable the starting of the injection to be controlled by the end of the piston, as set forth.

In testimony whereof I have signed my name to this specification.

JOSEF BENES.
